JAMES CONNOLLY, OF BOSTON, MASSACHUSETTS.

Letters Patent No. 60,696, dated January 1, 1867.

IMPROVED JOURNAL BOX.

The Schedule referred to in these Letters Patent and making part of the same.

TO ALL WHOM IT MAY CONCERN:

Be it known that I, JAMES CONNOLLY, of Boston, in the county of Suffolk, and State of Massachusetts, have invented an Improved Journal Box; and I do hereby declare that the following, taken in connection with the drawings which accompany and form part of this specification, is a description of my invention sufficient to enable those skilled in the art to practise it.

The invention relates to the construction of that class of journal boxes having oil reservoirs connected therewith, from which the lubricant is conveyed to the shaft by capillary attraction. The object of my invention is to provide such boxes with auxiliary chambers at each end, large enough for the shaft collars to run in, cast integral with the box and oil reservoir, and communicating with or leading from the reservoir, so that any oil which drips or is thrown from the collars shall be conveyed back to the main body of the lubricant. The invention consists, therefore, in a journal box, (having an oil reservoir forming part of it,) provided with extensions cast integral with the box, in which extensions form enlarged chambers of sufficient size for reception of the collars upon the shaft, which prevent longitudinal movement thereof, when said chambers communicate with or form part of the oil reservoir. The drawings represent a swinging journal box embodying my improvement, A showing a view of the same, partly in elevation and partly in central section; B, a plan of the lower half of the box; C, a cross-section on the red lines $x\ x$ and $y\ y$. a denotes the bearing; b , the babbitting thereof, on which the shaft c runs; d , the oil reservoir, cast with the bearing, a ; the space cored out between the reservoir and bearing containing the lubricant, which is fed up to one side of the shaft, through a wicking, e , by capillary attraction. In this construction the box does not differ materially from some others; but the reservoir, d , is extended beyond each end of the box, and enlarged at such extensions, the cups f , formed by such extension and enlargements, communicating with or forming part of the main reservoir, d , through openings, h . Such extensions are cast integral with the box, and in the cups, f , formed thereby, the collars i , of the shaft c , run, the cups f being of sufficient size to receive without contact the collars i . Over the box and cups, a cover k fits, keeping dust and dirt from the box and reservoir. The cups f serve to receive any oil which flows from the ends of the bearing, or which is thrown off from or drops from the collars, and to convey it back to the reservoir; and by casting the box, the reservoir, and these cups or extensions, all in one piece, the box is made neat in appearance, and more cleanly, cheaper, and more compact than where the parts are cast separately.

I claim the combination of the box or bearing, a , the reservoir d , and the enlarged extensions or cups, f , when of size sufficient to receive and protect the shaft-collars i , and when cast in one piece, substantially as described.

JAMES CONNOLLY.
